UNITED STATES PATENT OFFICE.

LEON M. CABANA, OF BUFFALO, NEW YORK.

NOZZLE FOR OIL OR OTHER BOTTLES.

SPECIFICATION forming part of Letters Patent No. 664,461, dated December 25, 1900.

Application filed May 31, 1899. Serial No. 718,911. (No model.)

To all whom it may concern:

Be it known that I, LEON M. CABANA, a citizen of the United States, residing at Buffalo, in the county of Erie and State of New York, 5 have invented new and useful Improvements in Nozzles for Oil or other Bottles, of which the following is a specification.

This invention relates to a nozzle for bottles and similar receptacles containing a liquid which it is desirable to discharge in small quantities or drops, such as lubricating-oil, perfumes, medicines, and liquid poisons.

The object of my invention is the construction of a simple and efficient nozzle of this kind which can be readily applied to a bottle—for instance, an ordinary oil-bottle—so that the bottle itself serves as an oil-can and which allows but a small quantity of liquid to flow from the bottle at a time, preventing 20 waste and soiling of the hands.

In the accompanying drawings, Figure 1 is a sectional elevation of an ordinary oil-bottle provided with my improved nozzle. Fig. 2 is a similar view of the upper portion of the bottle, showing the cap of the nozzle removed and the feed-rod pressed inwardly by contact with an object to be oiled. Fig. 3 is a horizontal section in line 3 3, Fig. 1. Fig. 4 is a sectional elevation of the upper portion of a 25 bottle, showing a modified construction of the nozzle.

Like letters of reference refer to like parts in the several figures.

A is an oil-bottle of any ordinary form.

35 B is the body of the nozzle, which consists of a tube provided near its upper end with a flange or rim b, which bears against the upper end of the neck of the bottle.

b' is a plug or stopper, of cork or other impervious material, applied to the portion of the tube B below its flange b and fitting tightly into the mouth of the bottle.

c is a feed rod or wire which is arranged to slide in the discharge tube or nozzle B and which is preferably pointed or tapered at its outer end. This rod does not fit the bore of the tube so snugly as to prevent the discharge of the liquid from the bottle or the entrance of air into the same, but is somewhat smaller 45 in diameter than said bore, so that a small annular space is left between the rod and the tube, through which the oil or other liquid is

allowed to escape only in drops or small quantities at a time. The feed-rod is provided at its inner end with a head or enlargement c', 55 forming a stop which limits the outward movement of the rod and prevents the same from falling out of the nozzle. If desired, the head or stop c' may also be utilized as a valve for reliably preventing the discharge of the liquid when the bottle is not in use, as shown in Figs. 1, 2, and 3. For this purpose a packing-washer d, of rubber or other suitable material, is preferably applied to the upper side of the head c', and a spring e is applied to the 60 projecting upper portion of the feed-rod between the upper end of the tube B and lugs or projections f, formed on the feed-rod near its upper end. The spring e is made of such a length that it tends constantly to move the 65 feed-rod to its outermost position, in which its valve-head bears against the inner end of the nozzle-tube and closes the same. The lugs or projections f, in conjunction with the spring e, act as a stop which limits the inward 70 movement of the feed-rod in the nozzle and prevents the same from falling into the bottle. The lugs f are cheaply formed after applying the spring to the feed-rod by flattening the adjacent portion of the rod on diametrically opposite sides thereof, causing the metal to spread and project beyond the 75 surface of the rod, as shown.

g is an ordinary screw-cap, which incloses the projecting upper portion of the feed-rod 80 and the spring e and engages with an externally-screw-threaded stem g', formed at the upper end of the nozzle B.

In lubricating a part with my improved oiler after removing the screw-cap g the bottle is 85 tilted or inverted, and the pointed outer end of the feed-rod is pressed or tapped against the part to be oiled, so as to cause the rod to slide inwardly against the pressure of the spring e and open the valve c', as shown in 90 Fig. 2. The oil escapes through the narrow space between the feed-rod and the surrounding tube and flows along the rod to the outer end thereof, thus supplying the oil in drops to the part in contact with the feed-rod. When 95 the flow ceases, the feed-rod is allowed to slide outwardly by gravity or under the reaction of the compressed spring e and again pressed against the part to be oiled, and so on until 100

the part is sufficiently lubricated. The spring *e* also acts as a spiral flange or thread, which further retards the flow of the oil toward the outer end of the feed-rod. By arranging this 5 spring on the outer side of the nozzle and utilizing the upper end of the nozzle as the inner abutment of the spring a simpler and less expensive construction is obtained than by arranging such a spring inside of the receptacle, 10 which arrangement requires a separate abutment for the spring below the nozzle.

As a modification of my invention the spring *e* may be omitted, as shown in Fig. 4, in which case the head *c* at the inner end of the feed- 15 rod serves only as a stop to prevent the rod from dropping out of the nozzle. In this modified arrangement the lugs *f* of the feed-rod act as outer stops, which prevent the rod from falling into the bottle. It will thus be ob- 20 served that in both of the constructions de- scribed the loose feed-rod is provided on the inner and outer sides of the nozzle with stops which limit its longitudinal play in the dis- charge-tube *B* in both directions.

25 By the use of my improved nozzle the bot-

tle or other receptacle requires no separate air-vent, the air entering the bottle between the nozzle-tube and the loose feed-rod, as hereinbefore described, thereby reducing the cost of the device and avoiding leakage, which is liable to take place when the body of the receptacle is provided with a vent.

I claim as my invention—

In a dropping-nozzle for ventless liquid-receptacles, the combination with the nozzle having a discharge-passage of uniform diameter from end to end, of a sliding feed-rod of correspondingly uniform diameter fitted snugly in said passage and projecting past the outer end of said nozzle and provided at its inner end with a head or enlargement and outside of the nozzle with integral flattened portions forming laterally-projecting lugs which limit the inward movement of the feed-rod in the nozzle, substantially as set forth.

Witness my hand this 27th day of May, 1899.

LEON M. CABANA.
